UNITED STATES PATENT OFFICE

RUDOLF WILHELM, OF ESSEN-ALTENESSEN, GERMANY, ASSIGNOR TO ARNOLD BECKERS, OF KÖLN-KALK, GERMANY

COKE OVEN

Application filed June 1, 1926, Serial No. 112,770, and in Germany June 16, 1925.

My invention relates to improvements in coke ovens, and more particularly to ovens provided with a frame for pressing a packing medium into a gap provided between the door and the frame thereof. The object of the improvements is to provide an oven of this construction in which the packing medium is pressed into the gap by means of pressing members provided with means for simultaneous operation from one part of the oven. With this object in view my invention consists in the matters to be described herein-after and particularly pointed out in the appended claims.

In the accompanying drawings,

Fig. 1, is an elevation showing one of the doors of a coke oven and the means for pressing the packing medium into the gap between the door and the frame,

Fig. 2, is an elevation looking from the side of the door,

Fig. 3, is a sectional plan view taken on the line 3—3 of Fig. 1,

Fig. 4, is an elevation similar to the one shown in Fig. 1 and illustrating a modification,

Fig. 5, is an elevation looking from the side of the door, and

Fig. 6, is a sectional plan view taken on the line 6—6 of Fig. 4.

In the example shown in Figs. 1 to 3 the front wall *v* of the oven is braced by anchors *v*¹ located at opposite sides of the door *b*. Between the door and the wall of the opening thereof an outwardly flaring gap *w* is formed which provides a seat for a suitable packing medium *h* running all around the door. The said packing medium is adapted to be pressed into tight contact with the wall of the gap by means of a frame consisting of an angle iron *i* and U-shaped transverse members *i*¹ located suitable distances apart, Fig. 1 showing five of the said members. The frame *i*, *i*¹ is mounted on the door *b* by means of

bracket *k* fixed to the door and permitting a slight movement of the members *i*¹ towards and away from the wall *v* of the oven. On bolts *a* fixed to the door *b* bars *a*¹ are rockingly mounted which are adapted to be rocked into position behind inclined lugs *c* in the

form of angle irons fixed to the anchors *v*¹ for holding the door *b* in position. In bores of the said bars clamping screws *g* are guided which are adapted for clamping engagement with plates *m* fixed to the members *i*¹ so as 55 to impart clamping pressure to the frame *i*, *i*¹. As appears from Figs. 1 and 2 the said plates *m* project from the members *i*¹ respectively upwardly and downwardly at the opposite sides of the doors, and the said projecting portions are inclined towards the wall of the oven, thus providing cam faces for the ends of the screws *g* when rocking the bars *a*¹ into clamping position. The screws *g* are adapted to be screwed inwardly more 60 or less for regulating the clamping pressure on the frame *i*, *i*¹. In some cases I provide the same at their inner ends with shoes *n* adapted for sliding engagement with the plates *m*.

The bars *a*¹ are connected with each other by a vertical link *d*, and the said link is formed with teeth *d*¹ engaged by a pinion *d*² secured on a shaft which also carries a hand-wheel *d*³. The shaft with pinion and hand-wheel is mounted in a slide *d*³ guided on the link *d* and the slide is connected to one of the bolts *a* by a swinging link *d*⁴. In this way the pinion is retained in contact with the rack teeth on the link *d* as the link swings 70 in the oscillating movement of the bars *a*¹.

The operation of the apparatus is as follows: For fixing the door in position the hand wheel *d*³ is turned in a direction for rocking the bars *a*¹ into the horizontal positions shown in Fig. 1 as has been indicated in the said figure by the arrow *x*. Thus the said bars engage with their outer ends the lugs *c* and force the door *b* inwardly. Further, the bolts *g* engage the inclined cam plates *m* thus forcing the packing medium *h* into the gap *w*, the clamping pressure being regulated once for all by screwing the screws *g* more or less inwardly.

In Figs. 4 to 6 I have shown a modification in which the frame *i* for pressing the packing medium into the gap *w* is acted upon by toggle joints connected to a common operating mechanism. The construction of the oven and the door is the same as has been 95 100

described with reference to Figs. 1 to 3, and the same letters of reference have been used to indicate corresponding parts. But the door is held in position by means separate from the means for forcing the packing medium into the gap, and any known or preferred means may be used for holding the door in position.

The frame for forcing the packing medium *h* into the gap *w* comprises only the angle iron *i* bent into rectangular form. At suitable distances apart brackets *o* are secured to the frame *i* and the said brackets are acted upon by toggle joints consisting of links *p*¹ and *p*², the links *p*¹ being rockingly mounted on pins *p*³ mounted in lugs *b*¹ provided on the door *b*. The links *p*¹ are formed with extensions *p*⁴. The said extensions are connected in pairs to transverse rods *r*, and all the rods are connected with each other by a link *s* formed at its middle with a screw-threaded portion *t*. The said screw-threaded portion is engaged by a hand wheel *u* the hub of which is held in position between eyes *u*¹ fixed to the door *b*.

For holding the door in position transverse bars *y* are rockingly mounted on the door and adapted to be rocked into locking position at the rear of the inclined lugs *y*¹ fixed to the anchors *v*¹, the operation of the said bars *y* being indicated in Fig. 4 by showing one of the bars respectively in full and broken lines.

The operation of the apparatus is as follows: The door is first fixed in position by means of the bars *y*, in which position the frame *i* is located in front of the packing medium *h*. Now the hand wheel *u* is rotated in a direction for pulling the link *s* downwardly in Fig. 1, so that the links *p*¹, *p*⁴ are rocked more or less into position perpendicular to the door *b*. Thereby the frame *i* is forced inwardly and on the packing medium *h*.

While in describing the invention reference has been made to particular examples embodying the same I wish it to be understood that my invention is not limited to the constructions shown in the drawings, and that various changes may be made in the general arrangement of the apparatus and the construction of its parts without departing from the invention.

I claim:

1. An oven structure, comprising a chamber having a doorway, a door fitting into the doorway so as to leave a gap around said door, contracting inwardly of the oven structure, between the door and the sides of the doorway, a packing medium in said gap, a frame around said door adapted to press the packing medium in said gap, lug means on the sides of the doorway, rockable bars on the door adapted to be moved into interlocking engagement with the lug means, and carrying clamping devices adapted to be actuated to

bear directly on the frame and move the frame against the packing medium, to thereby force and bind the packing medium in the gap, a link connecting the bars for moving them simultaneously, a pinion engaging rack teeth on the link, a hand wheel connected to the pinion for moving the link, and a mounting for the hand wheel and pinion upon the door.

2. In an oven structure, the combination of a doorway, a door fitting into the doorway so as to leave an outwardly flaring gap around the door, between the door and sides of the doorway, a packing medium in the gap and extending around the door, a frame around the door adapted when moved inwardly against the packing medium to press the latter into the gap, means to mount the frame on the door for relative movement with respect thereto, lug means on the doorway, rockable bars on the door adapted to be rocked into interlocking engagement with the lug means and carrying clamping devices adapted to be actuated to bear directly on the frame and move the frame inwardly against the packing medium, a link mounted for movement longitudinally of itself connecting the bars for moving them simultaneously, actuating mechanism for the link including a rotatable hand wheel and an operative connection between the link and hand wheel whereby to cause movement of the link upon the rotation of the hand wheel.

3. Mechanism for pressing and holding a packing in an outwardly flaring gap extending around a door between the door and its doorway, said mechanism comprising a frame around the door adapted when moved inwardly against the packing to press the latter into the gap, means to mount the frame on the door for relative movement with respect thereto, lug means on the doorway, rockable bars on the door adapted to be rocked into interlocking engagement with the lug means, bearing members provided on the frame, screw devices carried by the bars and adapted to be actuated to bear on the bearing members and move the frame inwardly against the packing, a link mounted for movement longitudinally of itself connecting the bars for moving them simultaneously, and actuating mechanism for the link including a rotatable hand wheel and an operative connection between the link and hand wheel whereby to cause movement of the link on the rotation of the hand wheel.

4. Mechanism for pressing and holding a packing in an outwardly flaring gap extending around a door between the door and its doorway, said mechanism comprising a frame around the door adapted when moved inwardly against the packing to press the latter into the gap, means to mount the frame on the door for relative movement with respect thereto, lug means on the doorway, rockable

bars on the door adapted to be rocked into interlocking engagement with the lug means, bearing members provided on the frame, clamping devices carried by the bars and
5 adapted to be actuated to bear on the bearing members and force movement of the frame inwardly against the packing, a link mounted for movement longitudinally of itself connecting the bars for moving them
10 simultaneously and provided with rack teeth, and means engaging said rack teeth to impart movement to said link.

In testimony whereof I hereunto affix my signature.
